UNITED STATES PATENT OFFICE

HARRY D. CLOUD, OF LEXINGTON, KENTUCKY, ASSIGNOR OF ONE-HALF TO WILLIAM M. INGRAM, OF LEXINGTON, KENTUCKY

WINDOW AWNING

Application filed August 28, 1931. Serial No. 560,013.

This invention relates to new and useful improvements in window awnings formed of sheet metal or other suitable rigid material.

Among the objects of the invention are to provide a plurality of awning sections which are detachably and pivotally connected as a unit to the attaching section whereby the latter may be easily secured to a window casing and the former may be easily connected to or disconnected from the latter; and to provide an operating means for positively swinging the sections into either an extended position or in a collapsed position and for retaining the sections in any adjusted position.

Another object of the invention is to provide an awning section operating means including novel worm screw and sleeve equipment by employment of which it is possible to positively and substantially noiselessly move the sections to the open or collapsed positions with a minimum of effort and without the need of utilizing lock detent or like equipments for securing the parts in adjusted positions.

With these and other objects in view which will more fully appear, the nature of the invention will be more clearly understood by following the description, the appended claims, and the several views illustrated in the accompanying drawings.

In the drawings:—

Figure 1 is a perspective view of an awning and operating means therefor which embodies my invention, the view showing the awning telescoped or collapsed and attached to a window casing.

Figure 2 is a sectional perspective view of my improved awning in its open condition, the view looking into one inside corner thereof.

Figure 3 is a perspective view of the rock shaft, links, and rack bar which form a part of the operating mechanism.

Figure 4 is a detail side elevation showing the pivotal connections between the sections of the awning.

Figure 5 is a vertical sectional view taken through the pivotal connections shown in Figure 4.

Figure 6 is an enlarged horizontal sectional view of the operating mechanism, the section being taken through the crank axis.

Figure 7 is a detail vertical section of the operating mechanism shown in Figure 6, the section being taken through the axis of the worm screw.

Figure 8 is a perspective view of one of the intermediate sections of the awning.

Figure 9 is an irregular sectional view taken through the sections on line 9—9 of Figure 2, the sections being shown extended.

Figure 10 is a detail sectional view illustrating the engaging portions of several of the awning sections which have been partially telescoped.

Like reference numerals designate corresponding parts throughout the several figures of the drawings.

In the drawings, I have disclosed the invention mounted on a window casing A which includes the usual ceiling beam 1 and side walls 2 and 3.

The awning comprises a plurality of sheet metal or other suitable rigid material sections which are nested or telescopically arranged to swing about pivots whereby they may be easily collapsed or extended. Preferably the awning comprises an attaching or top section B, a bottom section C, and a plurality of intermediate sections D, D' and D''. The attaching section B comprises triangular sides 4, 4 and a rectangular top or connecting portion 5 which is curved in cross section as illustrated in Figures 1 and 2. Each side 4 is provided along its casing engaging edge with an inwardly extending integral flange 6 and along its outer edge with a spacer flange 7 formed by bending the edge of the metal back upon the body as shown in Figures 9 and 10, and along its top edge with an inwardly extending flange 8, the top 5 being rigidly connected to the top flanges 8 of the sides by rivets, welding, or other means. The top 5 is provided along its rear edge with a depending integral flange 9. The section B is rigidly attached to the window casing by screws or other fastening means which pass through the rear side flanges 6, 6 and top flange 9. The lower edge of the flange 9 is

preferably rebent as at 10 to reinforce the flange. The top 5 along its front edge is provided with an integral depending flange 11 which terminates in an angularly bent inwardly extending lip or flange 12 which constitutes a stop and support for the other sections when the latter are extended, and also reinforces the depending flange 11 sufficiently to enable it to withstand the load of the other sections without buckling.

The intermediate sections are of like construction and therefore a description of one section will suffice. Each of these intermediate sections includes triangular sides 13, 13 and a flat rectangular top or connecting portion 14 which may be flange-secured to the sides as indicated at 14'. Each side 13 is provided along its inner edge with an inwardly extending integral flange 15, and along its outer edge with a spacer flange 16 formed by bending the edge of the metal body back upon itself. The top 14 is provided along its inner edge with an upwardly extending longitudinal flange 17, and along its outer edge with a downwardly extending longitudinal flange 18 which terminates in an inwardly extending longitudinal flange 19.

The bottom section C is similar to an intermediate section except that it lacks the flange 18, 19, and instead is provided with an inwardly directed channel bead 20 to which a sheet metal apron 21 is flange-secured as indicated in Figures 2, 5 and 9 of the drawings.

The intermediate sections D', D², and the bottom section C, are independently pivoted to the intermediate section D by pivot pins 22, 23 and 24, the pins connecting the sides of the respective sections. Thus the intermediate sections D', D² and the bottom section C constitute a unit, and this unit is adapted to be pivotally attached to and detached from the attaching section B by pivot bolts α which respectively engage the sides 4 of the attaching section B and the adjacent sides 13 of the intermediate section D.

Thus, assuming the awning sections to be extended, a lifting force imparted to the bottom section C, will cause the intermediate sections to be lifted therewith by reason of the flanges 15 engaging one another in succession. The flanges 7 of the section B and the flanges 16 of the intermediate sections constitute spacing means and reduce to a minimum friction between said flanges and the adjacent sections with which they slidably engage, as well as strengthen the sides of the sections, and also reduce to a minimum the possibility of rain and other foreign elements entering therebetween.

The ends 4, 4 of the rear section B are provided with pressed out ventilator openings 25, 25.

The flanges 18 of the intermediate sections

and the flange 11 of the top section cooperate with the flanges 17 of the intermediate and bottom sections when the sections are extended in forming limiting stops limiting extension movements of the sections to extend the sections, and the flanges 19 of the sections D, D' and D² and the flange 12 of the section B function to reinforce the flanges 18 and 11.

In order to positively collapse and extend the awning, I have provided the following mechanism:—

Journalized in hangers 27, 27 secured to the rear depending flange 9 of the attaching section B is a rock shaft 28 having crank arms 29, 29 at its opposite ends and projecting in the same angular direction. Pivots connected to each crank arm as at 30 is the upper end of a link 31, the lower ends of the links being respectively pivoted as at 32, 32 to clamps 33, 33 engageable with the channel beads 20 of the bottom section C. A vertically disposed operating bar 34 has its upper end pivotally connected as at 35 to one of the links 31 intermediate the ends thereof. The lower end of the bar is removably connected as at 36 to a worm rod 37 which is movable up and down through apertures provided therefor in the upper and lower legs of a stirrup or bracket 38 secured to the window casing. Within the bracket 38 the worm rod 37 threads through a worm sleeve 39 which is rotatable but is held against longitudinal movement by reason of being confined between the upper and lower legs of the bracket 38. The sleeve 39 carries a bevel pinion 40 which meshes with and is driven by a similar pinion 41 mounted upon one end of the operating shaft 42 which is rotatable in a suitable bearing provided therefor in the window casing and has its other end, preferably extended through to the interior of the building on which the awning is mounted, equipped with a turning crank 43. A suitable removable cover 45 may be provided to protect the sleeve and gears from the elements and also from inadvertent tampering.

It will be obvious that by rotating the crank 43 rotation will be imparted to the captive screw sleeve 39 which will move the worm rod 37 up or down accordingly as said crank is turned in one direction or the other. Thus the awning sections may be moved positively, substantially noiselessly and with a minimum of effort either to the collapsed or the extended position. Because of the employment of worm screw connections the parts are automatically secured at all positions to which they are adjusted and it is unnecessary to employ locking detents or similar equipments for this purpose.

The clamps 33 are adjustable along the channel beads 20 to permit of the operating parts being properly fitted to the awning.

From the foregoing, it will be observed that my awning may be readily applied to a window casing or removed therefrom. In applying the awning the attaching section B is first secured to the casing, and it will be noted that the rock shaft 28 has been previously mounted in the hangers 27 which are attached to the rear flange 9 of said attaching section. The remaining sections D, D', 10 D² and C which have been previously pivotally connected, are then attached as a unit by the pivot bolts 26 to the sides of the attaching section B. The links 31 are then connected to the cranks 29 of the rock shaft and to the 15 channel beads 20 of the bottom section C. The operating shaft 42 and handle 43 and the bracket 38 are then mounted on the window casing and the worm sleeve inserted between the upper and lower legs of the bracket with 20 its bevel pinion 40 in mesh with the pinion 41 carried by the shaft 42. The worm rod 37 may now be threaded into and through the sleeve 39 and connected at 36 to the operating bar 34 which is in turn connected at its other 25 end at 35 to the link 31.

If desired all of the sections may be provided at the pivot forming corners of their sides with reinforce plates 44 as shown in Figures 1, 2, and 8.

It is of course to be understood that the details of structure and arrangements of parts may be variously changed and modified without departing from the spirit and scope of the invention.

35 I claim:—

1. In a rigid material awning, the combination of a plurality of sections consisting of an attaching section, and a bottom section and intermediate sections pivoted to the attaching section; and operating means for positively telescoping and extending the bottom and intermediate sections, comprising a rock shaft having crank arms, links connecting the crank arms and the bottom section, an operating bar connected to one of the links intermediately of the ends thereof, and means to move the bar.

2. In a rigid material awning, the combination of a plurality of sections consisting of an attaching section, and a bottom section and intermediate sections pivoted to the attaching section; and operating means for positively telescoping and extending the bottom and intermediate sections, comprising a rock shaft having crank arms, links connecting the crank arms and the bottom section, an operating bar connected to one of the links intermediately of the ends thereof, and means to move the bar positively in one direction or another to positively extend or telescope the awning sections.

3. In a rigid material awning, the combination of a plurality of sections consisting of an attaching section, and a bottom section and intermediate sections pivoted to the at-

taching section; and operating means for positively telescoping and extending the bottom and intermediate sections, comprising a rock shaft having crank arms, links connecting the crank arms and the bottom section, an 73 operating bar, means to move the bar positively in one or the other direction of its length, and means for connecting the bar with one of the crank arms so that movement of the bar will be transmitted through the crank 75 arm to the rock shaft.

4. In a rigid material awning, the combination of a plurality of sections consisting of an attaching section, and a bottom section and intermediate sections pivoted to the attaching section; and operating means for positively telescoping and extending the bottom and intermediate sections, comprising a rock shaft having crank arms, links connecting 80 at one end to the crank arms and removably connected at their other ends to the bottom section, an operating bar connected to one of the links intermediately of the ends thereof, and means to move the bar.

5. In a rigid material awning, the combination of a plurality of sections consisting of an attaching section, and a bottom section and intermediate sections pivoted to the attaching section; and operating means for positively telescoping and extending the bottom and intermediate sections, comprising a rock shaft having crank arms, links connecting the crank arms and the bottom section, an operating bar connected to one of the links intermediately of the ends thereof, and means 90 including worm screw connections for positively moving the bar and for securing it at moved positions.

6. In a rigid material awning, the combination of a plurality of sections consisting of an attaching section, and a bottom section and intermediate sections pivoted to the attaching section; the attaching section including a top having a depending flange; and operating means for positively telescoping and extending the bottom and intermediate sections, comprising a rock shaft rotatably supported by the depending flange of the attaching section crank arms, links connecting the crank arms and the bottom section, an operating bar connected to one of the links intermediately of the ends thereof, and means to move the bar.

7. In a rigid material awning, the combination with an attaching section including 100 spaced sides and a connecting top, of a plurality of movable sections nested within the attaching section and pivotally connected together to form a unit, and detachable pivotal connections between the outermost nested 105 movable section and the sides of the attaching section.

8. In a rigid material awning, the combination with an attaching section including 110 spaced sides and a connecting top, of a plu- 115

- rality of movable sections nested within the attaching section and pivotally connected together to form a unit, detachable pivotal connections between the outermost nested movable section and the sides of the attaching section, and operating means for positively telescoping and extending the movable sections including a rock shaft extending transversely between the sides of the attaching section and having crank arms, links connecting the innermost movable section and the crank arms, and manually operable means connected to one of the links.
9. In a rigid material awning, the combination with an attaching section including spaced sides and a connecting top, of a plurality of movable sections nested within the attaching section and having pivotal connection with the attaching section, detachable pivotal connections between the outermost nested movable section and the sides of the attaching section, and operating means for positively telescoping and extending the movable sections including a rock shaft extending transversely between the sides of the attaching section and having crank arms, links connecting the innermost movable section and the crank arms, and manually operable means connected to one of the links.
10. In a rigid material awning, the combination with an attaching section including spaced sides and a connecting top, of a plurality of movable sections nested within the attaching section and having pivotal connection with the attaching section, detachable pivotal connections between the outermost nested movable section and the sides of the attaching section, and operating means for positively telescoping and extending the movable sections including a rock shaft extending transversely between the sides of the attaching section and having crank arms, links connecting the innermost movable section and the crank arms, and manually operable means connected to one of the links.
11. In a rigid material awning, the combination of a plurality of pivotally connected sections consisting of an attaching section, a bottom section and an intermediate section; and operating means for positively telescoping and extending the sections, comprising a rock shaft having crank arms, links connecting the crank arms and the bottom section, an operating bar connected with one of the crank arms, a worm rod carried by the bar, a screw sleeve through which the worm rod is threaded and which is held against longitudinal movement, and means to rotate the sleeve to impart longitudinal movement to the operating bar.
12. In a rigid material awning, the com-

bination of a plurality of pivotally connected sections consisting of an attaching section, a bottom section and an intermediate section; and operating means for positively telescoping and extending the sections, comprising a rock shaft having crank arms, links connecting the crank arms and the bottom section, an operating bar connected with one of the crank arms, a worm rod carried by the bar, a screw sleeve through which the worm rod is threaded and which is held against a rigidly supported bracket for holding the sleeve against longitudinal movement, a manually rotated shaft, and gear connections between the sleeve and the manually rotated shaft for the purpose described.

In testimony whereof, I have hereunto subscribed my name.

HARRY D. CLOUD.
